UNITED STATES PATENT OFFICE.

ISAAC SHRUM, OF NEVADA, MISSOURI.

REMOVABLE TRAY FOR TRAVELERS' BAGS.

1,291,201.

Specification of Letters Patent.

Patented Jan. 14, 1919.

Application filed September 3, 1918. Serial No. 252,371.

To all whom it may concern:

Be it known that I, ISAAC SHRUM, a citizen of the United States of America, residing at Nevada, in the county of Vernon and 5 State of Missouri, have invented certain new and useful Improvements in Removable Trays for Travelers' Bags, of which the following is a specification.

This invention relates to certain new and 10 useful improvements in removable trays for travelers' bags or valises and has among its main objects the provision of a device of this character which is exceedingly simple in construction although of great utility, the 15 tray being so constructed as not to require any side supports or hangers for the same when in use.

A further object of the device is the provision of a tray for carrying small articles 20 and adapted for arrangement within a traveling bag upon the larger contents thereof, such as clothing, and provided with cutout portions in the ends of the tray for reception of the infolding ends of the traveling 25 bag to securely maintain the tray in position.

With the above general objects in view and others that will become apparent as the 30 nature of the invention is better understood, the same consists in the novel form, combination and arrangement of parts hereinafter more fully described, shown in the accompanying drawing and claimed.

In the accompanying drawing forming 35 part of this application, wherein like characters of reference refer to corresponding parts throughout the several views,

Figure 1 is an elevational view of a traveling bag with the present invention arranged therein, a portion of the traveling bag being broken away and a portion of the tray being illustrated in longitudinal section.

Fig. 2 is a vertical transverse sectional view taken substantially upon line II—II of Fig. 1.

Fig. 3 is an enlarged detail fragmentary view taken substantially upon line III—III of Fig. 2.

Fig. 4 is an enlarged perspective view of the tray detached, and

Fig. 5 is an end view of a modified form of tray which may be used.

Referring more in detail to the several 55 views, an ordinary traveling bag 5 is shown having the usual hinged frame 6 at the top

thereof consisting in two parts which are swung toward each other for closing the bag, said frame being maintained closed by suitable locking means 7 and 8 as shown in 60 Fig. 1.

In traveling bags of this character, the closing of the frame 6 produces an infolding of the leather or other material constituting the body of the bag as shown at 9 65 in Figs. 1 and 2 and the present tray 10 has the ends thereof cut out as at 11 to accommodate these infolded portions.

The upper portion or sides of the bag 5 are usually inclined as at 12 and in order to 70 accommodate the tray 10 in this portion of the bag, the sides 13 of the tray 10 are inclined inwardly so as to prevent damage to the tray sides when the bag is closed.

The corners of the tray 10 are preferably 75 rounded as at 14 to enable the tray to be readily inserted within the bag and to allow a slight distortion of the body of the bag in order to be completely filled, at which time the corner portion 15 of the bag 5 may move 80 into contact with the corners 14 of the tray.

In order to provide for the ready removal of the tray 10, suitable tapes 16 are attached to the ends of the tray 10, which tapes may be readily engaged by the fingers 85 to readily lift the device and thereby remove the same from the bag 5.

In the use of the form of the invention above described, the traveling bag 5 is usually well packed with clothing 17 in the 90 bottom portion thereof and the tray 10 is then placed inside of the bag so as to rest upon the clothing 17 in substantially the position shown in Figs. 1 and 2. The tray may then be filled with small articles neces-

sarily carried by travelers such as brushes, shaving brushes, soap, small books, etc., and then the bag is closed so that the infolded portions 9 engage the edges of the cut out 95 portions 11 so as to securely maintain the tray against even slight movement. It is

obvious that ready access may be had to the articles carried in the tray without the removal of the clothing, etc., and the tray may be easily removed in order to gain access to 100 the clothing. The present tray is preferably made of fiber, pasteboard, leather or the like, and may be of any desired depth.

In the form of the invention illustrated in Fig. 5, the tray 10' has the ends thereof 110 cut out as at 11' to accommodate the infolded portions 9 of the bag and the ends

of the tray 10' are also provided with tapes 16' forming handles somewhat similar to the handles 16 hereinbefore described. The tray 10' is provided with sides 13' which are not sloped inwardly so that the tray may be utilized to advantage if placed slightly farther down into the bag 5 than the tray 10 is positioned as shown in Figs. 1 and 2. This form of tray will also be found useful in traveling bags which are not provided with slanting upper portions 12.

From the foregoing description, it is believed that the construction and utility of the present invention will be readily understood, it being noted that the bag 5 is opened at the top thereof and the tray is placed in the bag after other articles such as clothing, etc., are packed therein.

It will be apparent that the present invention presents a tray for travelers which is of great convenience and utility and which may be manufactured at a nominal cost.

While the forms of the invention herein

shown and described are what are believed to be the preferable embodiments thereof, it is nevertheless to be understood that minor changes may be made in the details thereof without departing from the spirit and scope of the invention as claimed.

What I claim as new is:—

1. A removable tray for travelers' bags comprising an open-top receptacle having the end walls thereof cut out for reception of the infolding ends of the traveling bag.

2. A removable tray for travelers' bags comprising an open-top receptacle having the end walls thereof cut out for reception of the infolding ends of the traveling bag, and handle forming tapes upon the ends of said tray adjacent the cut-out portions thereof.

3. A removable tray for travelers' bags comprising a receptacle having the end walls thereof cut out for the reception of the infolding ends of said traveler's bag, and handles upon said tray.

In testimony whereof I affix my signature.

ISAAC SHRUM.
